UNITED STATES PATENT OFFICE.

JACOB PFEIFFER, OF AKRON, OHIO, ASSIGNOR TO MILLER RUBBER COMPANY, A CORPORATION OF OHIO.

NIPPLE FOR NURSING-BOTTLES.

1,081,464.

Specification of Letters Patent. Patented Dec. 16, 1913.

Application filed September 16, 1913. Serial No. 790,089.

To all whom it may concern:

Be it known that I, JACOB PFEIFFER, citizen of the United States, residing at Akron, Ohio, have invented certain new and useful 5 Improvements in Nipples for Nursing-Bottles, of which the following is a specification.

My present invention is designed as an improvement upon the type of nipple patented by me under date of May 9, 1899, #624,859. 10 I have found that in the use of a nipple of the character shown in said patent the groove or channel is more or less difficult to keep properly cleansed and in a sanitary condition, and furthermore the opening, notwithstanding the channel in the stem, was 15 not entirely free from danger of becoming closed or clogged up.

The present invention has for its object to overcome these objections, and the invention 20 includes the novel construction hereinafter described and particularly defined by the appended claim.

A nipple constructed in accordance with my invention is illustrated in the accompanying drawings, in which—

Figure 1 is a longitudinal sectional elevation of the nipple; Fig. 2 is a transverse section on line 2—2 of Fig. 1 looking toward the top.

30 Referring by reference characters to this drawing, the numeral 1 designates the nipple which may be of the ordinary or any de-

sired shape, and 2 the stem which projects inward from the head of the nipple sufficiently far to prevent collapsing of the nipple. The stem is provided with a transverse slit or passage 3 entirely through it, and extending from the head backward a suitable distance, and the delivery opening 4 is in direct line with the center of this passage. 35 By extending the passage 3 entirely through the stem, I avoid the objectionable groove or channel which is difficult to cleanse, and thus make the nipple of a more sanitary nature, and furthermore I have found that by this 40 arrangement the opening 4 is less likely to become clogged, as it is not located in a corner, as was necessarily the case in my prior patent referred to.

Having thus described my invention what 50 I claim is:

A nipple for nursing bottles having a stem integral with the head or dome thereof, provided with an elongated transverse passage 55 extending entirely through the same and extending to the head or dome, the said head having an outlet orifice in line with said passage, substantially as described.

In testimony whereof, I affix my signature in presence of two witnesses.

JACOB PFEIFFER.

Witnesses:

FERDINAND BRUCKER,
RICHARD GRIFFITH.
